The ornamental design for a mobile phone shell, as shown and described.

DESCRIPTION

FIG. 1 is a first perspective view of a mobile phone shell showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 1.

The dot-dash broken lines in FIGS. 1 and 9 delineate a portion of the mobile phone shell, including claimed subject matter, that is shown on an enlarged scale in FIG. 9. The dashed broken lines shown in the drawings depict portions of the mobile phone shell that form no part of the claimed design.
